ENGINE STARTER

Donald L. Miller, Pine City, N. Y., assignor to
 Bendix Aviation Corporation, Elmira Heights,
 N. Y., a corporation of Delaware

Application October 15, 1945, Serial No. 622,331

9 Claims. (Cl. 74—7)

1

The present invention relates to engine starter gearing and more particularly to a drive of the automatically engaging type adapted to maintain operative connection until the engine is reliably self-operative.

It is an object of the present invention to provide a novel engine starter drive of the type above set forth which is efficient and reliable in operation, simple and compact in construction and adapted for economical manufacture.

It is another object to provide such a device in which a yielding member is used in the driving connection, by which the load is progressively picked up.

It is another object to provide such a device which is adapted to connect a starting motor to a member of an engine to be started and to maintain such connection as long as the starting circuit is energized.

It is another object to provide such a device which enables the engine to overrun the starting motor quietly and without danger of jamming.

It is another object to provide such a device which is dependent on the speed of rotation of the starting motor to keep the gearing engaged.

It is another object to provide such a device with a means of opposing the disengagement of the driving member until the starting motor begins to decelerate.

It is another object to provide such a device having two threaded members of different pitch; the member having the higher pitch thread serving to traverse a drive pinion into and out of mesh with an engine gear, while the member of lower pitch controls an inertia member to oppose demesh of the pinion.

Further objects and advantages will be apparent from the following description taken in connection with the accompanying drawing, in which:

Fig. 1 is a side elevation partly in section showing a preferred embodiment of the invention with the parts in idle position;

Fig. 2 is a similar view showing the parts in the positions assumed during the cranking operation;

Fig. 3 is a similar view showing the parts in the positions assumed when the engine starts and overruns the drive while the starting motor is still in operation;

Fig. 4 is a detail view in perspective of the differentially threaded drive shaft; and

Fig. 5 is a detail view in perspective of the inertia blocking member, the spacing ring and the control nut in disassembled relation.

2

In Fig. 1 of the drawing, there is illustrated a power shaft 1 which may be the armature shaft of a starting motor not illustrated. The power shaft has a reduced extension 2 forming a shoulder 3, and an engine driving member 4 in the form of a pinion is slidably journaled on said extension for movement longitudinally into and out of mesh with a gear 5 of an engine to be started, said shoulder forming a stop for defining the operative position of the pinion.

An actuating member in the form of a hollow sleeve 6 having a threaded portion 7 of low pitch, and a second threaded portion 8 of higher pitch, is fixedly mounted on the power shaft 1 by any suitable means such as a cross pin 9 retained by a spring ring 10. A blocking member in the form of a nut 11 is threaded on the portion 7 of sleeve 6 having a comparatively low pitch, and is retained by a thimble 12 which is adapted to enter a counterbore in the end of sleeve 6 and is anchored on power shaft 1 by the pin 9. Thimble 12 has a radial flange 13 which defines the normal position of blocking nut 11, the forward movement of said nut being defined by a shoulder 14 at the end of thread 7.

A control nut 15 is threaded on the portion 8 of sleeve 6 having a comparatively high pitch, and is separated from said blocking nut by a spacing ring 16 which is journaled on the rear of the control nut and held in place by a lock ring 17. The adjacent surfaces of the blocking nut and spacing ring are preferably formed with undulations or inclined abutments 18 and 19, respectively, in order to overcome any tendency of these members to wedge or stick together.

An elastic member in the form of a cylindrical rubber block 20 is seated on the control nut 15, bearing at one end against a radial flange 21 of the nut and at the other end against a radial flange 22 of a thimble 23 which is mounted in telescopic relation with control nut 15. A barrel member or casing 24 is arranged to house the rubber block and is slidably journaled at one end on the flange 21 of the control nut, being retained thereon by an inturned lip 26. The other end of the barrel is provided with notches 27 adapted to receive radial lugs 28 on thimble 23 so as to anchor the thimble to the barrel. A driving clutch member 29 having teeth 30 is slidably journaled on the power shaft 1 and has radial lugs 31 which are arranged to enter the notches 27 of the barrel and are held therein by lock wire 32 so as to connect said elements for rotation and longitudinal movement in unison. 55 A driven clutch member 33 having teeth 34 is

fixedly mounted on the pinion 4 and is normally held spaced from the driving clutch member 29 by a spring 35 interposed therebetween. The separation of the clutch members is limited by a sleeve 36 surrounding the clutch members having an inturned flange 37 which with a washer 38 forms a thrust bearing for the driven clutch member, and having radial lugs 39 seated in the notches 27 of the barrel and retained therein by the lock ring 32.

Means for normally holding the control nut 15 in idle position is provided comprising a ball member 40 slidably mounted in a radial opening in the control nut and pressed against the threaded sleeve 6 by means of a spring ring 41, seated in a circumferential groove 43 in the control nut. The sleeve 6 is preferably provided with an inclined shoulder 42 in position to be engaged by the anti-drift ball 40 when the parts are in idle position.

In operation, when the starting motor is energized, the power shaft 1 rotates the screw sleeve 6, thereby moving the control nut 15 forward on the high pitched thread 8, which motion is transmitted through the rubber block 20, driving clutch member 29, spring 35 and driven clutch member 34 to the pinion 4 to advance the pinion into mesh with the engine gear. If the teeth of the pinion should abut against the ends of the engine gear teeth, the spring 35 will yield and permit the clutch 29, 33 to close and index the pinion teeth into registry with the tooth spaces of the engine gear, whereupon said spring expands and snaps the pinion forward, and the meshing movement proceeds. When the longitudinal movement of the pinion is arrested by the shoulder 3, further rotation of power shaft 1 torques and compresses the rubber cylinder 20 forcing the driving clutch member 29 into engagement with the driven clutch member 33 and thereafter yieldably transmitting the rotation of the starting motor to the pinion 4 to crank the engine. At the same time, due to the rotation of the screw sleeve 6, the blocking nut 11 also moves forward on the low-pitched threads 7 until it is stopped by the shoulder 14 at the end of said threads. It is then in a position to oppose demeshing movement of the control nut.

When the engine fires, the consequent acceleration of the pinion 4 is transmitted through the clutch 33, 29 and rubber block 20 to the control nut, causing it to overrun the screw sleeve 6 and start back toward idle position, thereby permitting the spring 35 to open said clutch and allow the pinion to overrun. Since at this time the drive shaft 1 is also being accelerated by the starting motor (although at a lower rate) due to the relief of the cranking load therefrom, the blocking nut 11 is firmly held against the stop shoulder 14 in position to engage the spacing ring 16 and thereby arrest the demeshing movement of the control nut 15 as shown in Fig. 3. Any momentary tendency there might be for the control nut to frictionally pick up and rotate the blocking nut is obviated by making the pitch of the threads of the control nut higher than that of the blocking nut so that if the nuts should attempt to rotate in unison on the screw shaft, they will approach each other and lock up.

If the engine should not continue to run, cranking will be resumed as soon as the pinion slows down to the speed of the starting motor, the spring 35 generating sufficient friction to ensure the proper traversal of the control nut. When the engine is reliably self-operative, the operator de-

energizes the starting motor whereupon the deceleration of the motor shaft causes both the blocking and control nuts to thread themselves back on the screw shaft to idle position.

5 Although but one embodiment of the invention has been shown and described in detail, it will be apparent that other forms are possible and changes may be made in the arrangement and proportions of the parts without departing from 10 the spirit of the invention.

What is claimed is:

1. In an engine starter, a motor shaft, a pinion slidably journaled thereon for movement into and out of mesh with an engine gear, means responsive to acceleration of the motor shaft for moving the pinion into mesh with the engine gear and thereafter yieldably connecting the pinion to rotate with the motor shaft, a blocking member movable longitudinally along the motor shaft, and means responsive to acceleration of the motor shaft for moving the blocking member into position to hold the pinion in mesh with the engine gear.

2. In an engine starter, a power shaft, a pinion 25 slidably journaled thereon, a screw sleeve fixed on the power shaft, means including a control nut threaded on the screw sleeve for moving the pinion into mesh with an engine gear and thereafter connecting the pinion to rotate with the 30 power shaft, and a second nut threaded on the screw sleeve and movable by acceleration of the screw sleeve into position to prevent demeshing the pinion.

3. An engine starter comprising a power shaft, 35 a pinion slidably and rotatably mounted thereon, a screw sleeve connected to rotate with the power shaft, means including a control nut threaded on the screw sleeve for moving the pinion into mesh with a gear of an engine to be started, and thereafter connecting the pinion to rotate with the power shaft, and a blocking nut on the screw sleeve in tandem relation with the control nut and movable by acceleration of the screw sleeve into the path of movement of the control nut.

4. In an engine starter, a power shaft, a pinion 45 slidably journaled thereon, a screw sleeve fixed on the power shaft, means including a control nut threaded on the screw sleeve for moving the pinion into mesh with an engine gear and thereafter connecting the pinion to rotate with the power 50 shaft, and a second nut threaded on the screw sleeve and movable by acceleration of the screw sleeve into position to prevent demeshing the pinion, said second nut being traversed backward 55 to permit demeshing of said pinion by deceleration of said power shaft.

5. In an engine starter, a power shaft, an actuating member fixed thereon, a driving member 60 slidably journaled on the power shaft, means including a control member cooperating with said actuating member for moving the driving member into and out of engagement with a member of an engine to be started, said means further including a clutch between said control member and driving member; and a blocking member on the actuating member movable by acceleration of the actuating member into position to oppose disengagement of the driving member from the engine member; including further a spacing ring swivelled on the control member separating the blocking member from the control member.

6. In an engine starter, a power shaft, an actuating member fixed thereon, a driving member 65 slidably journaled on the power shaft, means

including a control member cooperating with said actuating member for moving the driving member into and out of engagement with a member of an engine to be started, said means further including a clutch between said control member and driving member; and a blocking member on the actuating member movable by acceleration of the actuating member into position to oppose disengagement of the driving member from the engine member, in which the actuating member is in the form of a screw sleeve, the control member and the blocking member being threaded on said screw sleeve in tandem.

7. In an engine starter, a power shaft, an actuating member fixed thereon, a driving member slidably journaled on the power shaft, means including a control member cooperating with said actuating member for moving the driving member into and out of engagement with a member of an engine to be started, said means further including a clutch between said control member and driving member; and a blocking member on the actuating member movable by acceleration of the actuating member into position to oppose disengagement of the driving member from the engine member, in which the actuating member is in the form of a screw sleeve having high and low-pitched threads, the control member and blocking member being in the form of nuts threaded on the high and low-pitched threads respectively, and said screw sleeve having a shoulder forming a stop for the blocking member.

8. In an engine starter, a power shaft, a pinion slidably journaled thereon for movement into and out of mesh with a gear of an engine to be started, means movable longitudinally responsive to acceleration of the power shaft for moving the pinion into mesh with the engine gear and thereafter connecting the pinion to rotate with the power shaft, said means including a clutch and means for closing the clutch by final lon-

gitudinal movement after the pinion is fully meshed, and opening the clutch when the pinion overruns the power shaft; and means responsive to acceleration of the power shaft for preventing retrograde movement of the longitudinally movable means sufficient to demesh the pinion; said means for preventing retrograde movement being in the form of a blocking member and means responsive to acceleration of the power shaft for moving the blocking member into the path of movement of the longitudinally movable means.

9. In an engine starter, a power shaft, a pinion slidably journaled thereon for movement into and out of mesh with a gear on an engine to be started, means movable longitudinally responsive to acceleration of the power shaft for moving the pinion into mesh with the engine gear and thereafter connecting the pinion to rotate with the power shaft, said means including a clutch and means for closing the clutch by final longitudinal movement after the pinion is fully meshed, and opening the clutch when the pinion overruns the power shaft; and means responsive to acceleration of the power shaft for preventing retrograde movement of the longitudinally movable means sufficient to demesh the pinion; said means for preventing retrograde movement being in the form of a blocking member and traversing means therefor, said traversing means operating responsive to deceleration of the power shaft to move said blocking member to idle position.
